UNITED STATES PATENT OFFICE

JULES GASTON DALOZ, OF COURBEVOIE, FRANCE

ELECTRIC MINE LAMP

Application filed November 16, 1928, Serial No. 319,785, and in Belgium July 27, 1928.

The present invention relates to electric mine lamps of the type provided with a bulb operating inside a chamber containing gas under pressure.

8 One of the objects of the invention is to provide improved means for producing and maintaining gaseous pressure inside the pressure chamber.

10 Another object is to provide means for opening the circuit feeding the lamp bulb as soon as the globe containing gas under pressure breaks.

15 A further object is to provide means for compensating losses of gas from the pressure chamber.

A still further object is to provide means for indicating loss of pressure fluid so as to warn the miner that the lamp is about to be extinguished.

20 Additional objects will appear in the course of the detailed description now to be given with reference to the accompanying drawings, in which;

Fig. 1 is an axial section through one illustrative embodiment of the invention showing the pressure chamber in charged position;

25 Fig. 2 shows a possible variant of the lamp supporting structure represented in Fig. 1;

Fig. 3 represents, in section, a second form 30 of lamp assembly;

Figs. 4 and 5 are sections illustrating a third embodiment of the invention;

Fig. 6 is a detail showing a possible variant 35 of the structures represented in Figs. 3 to 5;

Fig. 7 represents a special assembly adapted to be used in the special case where the pressure chamber is filled with a liquid instead of a gas.

40 Referring to Fig. 1 of the drawings, there is shown a lamp assembly consisting of a globe *a* adapted to contain gas or a liquid under pressure,—a battery casing *b* provided with a threaded portion *b*¹,—a battery *c* fitted with resiliently supported contacts *d*,—a top-casing *e* formed with a flange *e*¹ adapted to coact with globe *a* and a threaded portion *e*² adapted to engage with *b*¹,—a rubber membrane *f* having its outer extremity stretched over flange *a*¹ of globe *a*,—a bulb *g* having its metallic portion *g*¹ supported by the minor

extremity of membrane *f* in contact with current terminals hereinbelow described,—a lamp base comprising an insulating plate *h* supported on threaded ring *i* in contact with membrane *f*, a central lamp terminal *j* connected to a first contact *j*¹, and a peripheral lamp terminal *l* urged upwardly by spring *k* which is in conductive relation with a second contact terminal *k*¹,—and finally a small metal ball *n* supported between slightly cupped surfaces formed on the bottom of *g*¹ and on the top of *j*.

The lamp is prepared for use in the following manner: An appropriate gas or liquid is first introduced into globe *a*; the interior portion of membrane *f* is then stretched over base *g*¹ of lamp *g* and the exterior portion over the mouth of globe *a* so as to cover both faces of flange *a*¹; metallic "skirt" *l* is then inserted under membrane *f* and is followed by spring *k* and plate *h* together with the various structures supported by or inserted in, the latter; the assembly then occupies a position corresponding to that shown in Fig. 3; as plate *h* is raised upward, membrane *f* compresses the fluid inside globe *a*, so that when annular ring *i* is finally screwed into place, globe *a* contains fluid sealed hermetically therein under pressure by a double packed joint composed of rigid elements *e*¹, *a*¹ and *h* and compressible element *f* covering opposite faces of flange *a*¹. To light bulb *g*, it suffices only to screw the battery assembly into place so that elements *d* contact with terminals *j*¹ and *k*¹. If globe *a*, breaks or is broken, the fluid under pressure therein is released and spring *k* pushes upward on skirt *l* so as to move bulb *g* out of contact with central electrode *j* thus extinguishing the lamp. Since the opening of the lighting circuit *j*, *g* occurs under membrane *f* there is no danger of the spark so produced igniting mine gases in the vicinity. The function of ball *n* is to prevent the miner attempting to relight the lamp.

It is to be noted that when skirt *l* is pushed upward, ball *n* is no longer held in position by bulb *g*. The slightest movement of element *j* will therefore cause ball *n* to fall off of its perch thus leaving a gap between *g* and *h*.

j which cannot be filled by manoeuvring either of these elements.

In the form of device illustrated in Figs. 3 to 5, the rubber membrane *f* shown in Fig. 1 is replaced by a similar element formed so that a portion thereof runs part-way up the inside of globe *a*, while a narrow flanged portion *f*¹ fits under flange *a*¹ and is sealed in position by an annular clip *a*² compressed between elements *e*¹ and *h*. In this form of membrane, the stretching effect on the external portion represented in Fig. 1 as covering both faces of flange *a*¹, is eliminated, and the life of the membrane greatly increased. The lamps shown in these figures differ otherwise from the one shown in Fig. 1 only in the form of the safety device (equivalent of ball *n*) for preventing relighting of the lamp by the miner. In the form of safety device shown in Fig. 3, element *j* is made in the form of a tubular shell split at its lower end so as to present a series of tongues *j*^o bent slightly outward and contacting *j*². When globe *a* breaks, tube *j* is lifted out of contact with *j*² by spring *k* and tongues *j*^o spread enough to prevent their reentry inside *j*² when attempts are made to lower *j* back into position. It is to be noted that the elevation of *l* and *j* is effected by the pressure of spring *k* on a pin traversing both of these elements and that skirt *l* is here shown as extending upward so as to embrace metal portion *g*¹ of bulb *g*. The safety device represented in Figs. 4 and 5 consists of a movable stem *j* a triangular or other non-circular lower portion fitting through a similarly shaped orifice *h*^o and contacting with a guided pedestal *o* urged upward by a spring *o*¹. The head of stem *j* is rotatably supported in an insulating element connected to skirt *l*. When globe *a* breaks, skirt *l* is projected upward by spring *k* and stem *j* slides through orifice *h*^o. It is evident that the miner will find it difficult, if not impossible, to readjust the position of stem *j* so that the proper angular relation with orifice *h*^o may be reestablished. Fig. 5 shows how stem *j* may be guided back into *h*^o by some authorized person other than the miner.

Figs. 2 and 6 show variants of the safety devices illustrated in Figs. 1 and 3 to 5 respectively. In the structure represented in Fig. 2, ball *n* (Fig. 1) is replaced by an assembly consisting of an insulating disc *m* having an orifice therethrough permitting contact between *j* and *g*, and a spring *m*¹ supported on skirt *l*. When globe *a* breaks and skirt *l* moves upward, spring *m*¹ moves disc *m* so that the orifice through the latter is out of line with element *j* and the miner is therefore unable to reestablish the contact *g*, *j*. In the device shown in Fig. 6, a central movable electrode *j* mounted to follow the movements of skirt *l* in the manner of the structures illustrated in Figs. 3 to 5, receives current from terminal *j*¹ through the inter-

mediary of a spring *q*³ and a composite slideable contact *q* having an upper insulating surface *q*² and a lower conducting surface. When skirt *l* raises rod *j*, a spring *q*¹ forces contact *q* in under the latter so that insulating surface *q*² comes under said stem and prevents the conductive relation between *j* and *j*¹ to be reestablished. This form of device is designed to be built into plates *h*, a screw in line with spring *q*³ permitting the latter to be retracted so as to move *j* back into operative position.

The variant shown in Fig. 7 is designed for the special case in which globe *a* is filled with water or some other electrically conducting liquid. The lamp assembly here remains the same as that shown in Figs. 1 or 3 to 5 but, in order to prevent deterioration of rubber membrane *f* by electrolysis which normally would take place, specially at *f*², as a result of the contact of metal element *g*¹ with the pressure liquid, bulb *g* is formed with a basal glass rib *g*² adapted to receive the inner extremity of the rubber membrane. Element *g*¹,—and also skirt *l*—are thus insulated from the pressure liquid and electrolytic effects which might otherwise be produced, are entirely eliminated.

The principal object of the present invention being to avoid the necessity of pumps and other auxiliaries for introducing and maintaining a gas under pressure in globe *a*, it will at once be evident, that the hereinabove described structures attain this object in a simple and practical manner.

It is to be understood, of course, that certain details of construction are not limited to the particular form of lamp structure illustrated in any one figure. Thus, skirt *l* may either extend up to element *g*¹, as in Fig. 1, or embrace the latter as in Figs. 3 to 5 and 7; the safety devices shown in Figs. 1, 2, 3, 6 or 4 and 5 may be used interchangeably with the forms of base *h* and skirt *l* illustrated in other of the figures, it being obvious that persons skilled in the art will at once be able to regroup and modify the various cooperating elements to obtain a workable combination. Finally, it is to be understood that the various safety devices equivalent to ball *n* in Fig. 1 constitute an optional, and not a necessary, part of the lamp assembly and may, if desired, be eliminated entirely. Thus, in Fig. 1, ball *n* may be left out and central electrode *j* extended so as to contact directly with the central contact of bulb *g*.

It has been found practicable to introduce volatile substances of the nature of chloroform into globe *a* to compensate for any losses occurring through the joints.

In the course of the use of the lamp, skirt *l* may rise gradually, because of leakage losses, and finally extinguish the lamp. To warn the miner of such an eventuality globe *a* may

be engraved or marked at a point indicating the level above which the tip (or the base) of bulb *g* must not rise.

What I claim is:—

5. 1. In electric lamps containing an electric bulb adapted to operate in a fluid under pressure, a fluid pressure producing assembly comprising a vitreous globe, a flexible membrane, a closure element for said globe, and
10 means operative to force said membrane away from said closure and towards said globe when said closure is moved into operative position, said means having portions thereof lying in contact with the membrane
15 and being displaceable both with relation to said globe and to said closure element.
2. In an electric lamp, a vitreous globe having a compressed fluid medium therein, an electric bulb provided with external metallic terminals and adapted to be inserted into said globe, a flexible membrane supported on said rigid element, and having its outer periphery formed to coact with the open end of the vitreous globe, a closure element formed to seal the open end of the vitreous globe, a rigid element shaped to contact electrically with one of the metallic terminals of said bulb, said rigid element being independent of, and displaceable with relation to said closure element and said globe, a conductor positioned to conduct current to one of the metallic terminals of the electric bulb, contacts positioned on the exterior side of the closure element and in conductive relation with the conductor and the rigid element, and means for supplying current to said contacts.
3. An apparatus as defined in claim 2 in combination with resilient means interposed
40 between the rigid element and the closure and tending to force the former away from the latter.
4. An apparatus as defined in claim 2 in combination with resilient means interposed
45 between the rigid and the closure elements tending to separate these latter, and a spherical electrical conductor interposed between the said conductor and the cooperating bulb terminal held in position by the fluid pressure in said globe.
5. An apparatus as defined in claim 1 in combination with means for conducting current to said bulb, and comprising a spherical electrical conductor held in position by the fluid pressure in said globe.

In testimony whereof I have signed this specification.

JULES GASTON DALOZ.
